UNITED STATES PATENT OFFICE.

EVAN B. MORRIS, OF CEDAR BLUFFS, NEBRASKA.

FARROWING HOUSE.

Application filed March 15, 1924. Serial No. 699,552.

My invention relates to farrowing houses together by bolts A as represented in Fig. 1, and the adjoining edges of the roof-sections are similarly secured to each other. At the center or apex of the roof there is an 60 opening which is fitted with a ventilator 10. Preferably the floor-section 18 is mounted on skids or runners 19, to facilitate moving the building for short distances without taking the sections thereof apart. 65

Within the described building I provide a plurality of removable partitions 2 which extend in from the side-walls toward the center, to form a series of substantially triangular pens of which the outer ends are 70 formed by the respective side-walls. One special partition 16 is provided as represented in Fig. 1, said partition and the adjacent regular partition 2 forming between them an alley or passage extending in from 75 the door 7 to the attendant's platform or walk around the heater. The partitions 2 at their inner ends are detachably connected with vertical posts 12 which are set uniformly about the center of the building, said 80 posts extending from the floor to the roof and being detachably connected therewith. Adjacent to the floor, partition-members 11 are extended in from the posts 12 to the center of the floor, said members being in effect 85 low extensions of the main partitions 2, and the spaces between them forming continuations of the main portions of the respective pens. At the center said members 11 constitute a support for the heater, which may 90 be a small oil-burning stove. The outer portions of the members 11 support the walk or hexagonal platform 3 which is disposed immediately within the circle of posts 12. The opening through the central part of the platform is covered by the hover 4 which 95 encloses the stove and serves to reflect the heat therefrom down into the apical portions of the pens between the partition members 11. The hover has a central opening 6, and the 100 stack or smoke-pipe 20 from the stove may be extended through the same and on upward through the ventilator 10, as shown in Fig. 3. Cross partitions 5 are extended between the posts 12 above the level of the walk 105 or platform 3, said partitions forming the inner ends of the main pens, to which the sows are confined. The low pen-extensions formed beneath the platform 3 and hover, and separated by the members 11, are uniformly 110 warmed by the heating means, and are freely accessible to the young pigs, while

5 10 15 20 25 30 35 40 45 50 55 60 65 70 75 80 85 90 95 100 105 110

the adult animals are excluded therefrom and thus prevented from injuring the young. At the side adjoining the entrance alley from the door 7, the cross-partition 5 is made shorter than the others, to allow free access to the walk or platform 3, from which the attendant may inspect and feed the animals in each pen, without disturbing them by passing through the pens, and may also take care 10 of the stove or heater.

It will be seen that the described structure provides a plurality of separate pens, each suitable for one sow and her litter, and each pen having an artificially heated portion to 15 which the young pigs may freely enter and from which the sow is excluded because of the small height thereof. The use of a single stove or heating device for all of the pens enables economical use of fuel, while supplying 20 all of the heat required for the several litters of pigs. By the removal of the main partitions 2, all of the pens may be combined to form a colony-house, which may be heated, if desired, by leaving in place the 25 structures within the circle of posts 12. When heating is not needed, the posts and other central structures may also be removed, to provide additional floor-space for the colony-house.

30 Now, having described my invention, what I claim and desire to secure by Letters Patent is:

1. In a farrowing house, a plurality of low partition members extending radially from 35 a common center, heating means including a hover supported upon the central portions of said partition members, a platform supported upon the outer portions of said members, and means forming a plurality of pens communicating respectively with the spaces between the low-partition members beneath the platform and hover.

2. In a farrowing house, means forming a plurality of pens having side portions which 45 extend radially of a common center, low extensions of said pen side portions continuing therefrom respectively to said center, whereby to divide the space about said center into a plurality of compartments each communicating with one of the pens, and a heating means arranged symmetrically to the several compartments.

3. In a farrowing house, the combination 55 with a building structure having a roof, floor, and side-walls; of a plurality of vertical posts spaced about a central point in said building structure, partitions extending from said posts to the side-walls to form a plurality of main pens, cross partitions extended between the adjacent posts to form the inner ends of said main pens, a heating means arranged within the polygonal space defined by said cross-partitions, and low par-

tition members dividing said polygonal space adjacent the floor into a plurality of compartments adapted to be warmed by the heating means, the cross partitions terminating above the floor whereby to form openings of restricted height connecting the main pens and the respective heated compartments. 70

4. In a farrowing house, a polygonal building structure, partitions extending in radially from the side-walls thereof to form a plurality of substantially triangular pens, centrally disposed heating means arranged 75 to warm the adjacent apical portions of the several pens, and means for excluding large animals from said apical pen-portions while allowing access of small animals thereto.

5. In a farrowing house, the combination 80 with a building structure having a roof, floor, and side-walls; of a plurality of partitions extending in from the side-walls toward a common center whereby to divide the floor-space into a plurality of substantially triangular pens, doors in the side-walls affording access to each of said pens, means for excluding large animals from the adjacent apical portions of the pens, said means permitting access of small animals to 90 said portions of the pens, and a heater for warming said portions of the pens.

6. In a farrowing house, the combination 95 with an inclosure having a roof, floor, and side-walls; of a plurality of main partitions extending from the side-walls toward a center and dividing the floor-space into a plurality of pens each having a portion adjacent to said center, a heater arranged at said center and adapted 100 to warm the adjacent portions of the pens, a walk supported upon the partitions about the heater, and cross partitions extending between the main partitions upwardly from said walk, said cross partitions and walk 105 being arranged at a height from the floor suitable for excluding large animals from the warmed portions of the pens while permitting smaller animals to pass beneath said walk and partitions into the warmed pen-portions.

7. In a structure of the class described, a polygonal building, a plurality of radially extending partitions removably disposed therein for dividing the same into substantially triangular pens, and means for excluding from the central apical portions of the pens animals of a size larger than a determined minimum, said means covering the central space common to the apical portions of the several pens and thereby serving to retain in said common space the body-heat 115 from the smaller animals of all of the pens. 120

In testimony whereof I affix my signature.

EVAN B. MORRIS.
